UNITED STATES PATENT OFFICE.

GEORGE J. MARION, OF COTTER, ARKANSAS, ASSIGNOR OF ONE-HALF TO ALVA M. SMITH, OF CUSHMAN, ARKANSAS.

STOVE-OVEN.

1,371,105.

Specification of Letters Patent.

Patented Mar. 8, 1921.

Application filed November 19, 1918. Serial No. 263,201.

To all whom it may concern:

Be it known that I, GEORGE J. MARION, a citizen of the United States, residing at Cotter, in the county of Baxter and State of 5 Arkansas, have invented new and useful Improvements in Stove-Ovens, of which the following is a specification.

This invention comprehends generally improvements in that class of inventions 10 known as stoves and furnaces, and more particularly relates to a stove oven.

It is the primary aim and object of the present invention to provide a device of the above mentioned character wherein a false 15 bottom is provided for the oven and preferably connected to the door so that it may be moved outwardly and over the door upon the opening thereof to consequently draw the baking-pan adapted to be disposed on 20 the false bottom from the oven when desired.

More particularly the present invention consists in the provision of a device of the above mentioned character wherein improved 25 manually operable latch means is mounted on the door for coöperating with the false bottom to either assure of the movement of the false bottom outwardly simultaneously with the opening of the door 30 or for permitting of the opening of the door without moving the false bottom.

Among the other aims and objects of this invention may be recited the provision of a device of the character described with a 35 view to compactness, and in which the parts are few, the construction simple and the cost of production low and the efficiency high.

Other improvements and novel details in 40 the construction and arrangement of the various parts of the apparatus will be brought out more in detail in the description to follow, which for a clear understanding of the invention should be considered 45 in connection with the accompanying drawings forming a part hereof, and wherein is disclosed for the purpose of illustration a convenient and satisfactory embodiment of the invention. It is to be 50 noted in this connection that minor changes in the construction and arrangement of parts may be made without departing from the principle of operation of the various parts.

The invention is clearly illustrated in the 55 accompanying drawings:—

Figure 1 is a transverse section taken through the device showing the same closed.

Fig. 2 is a similar view showing the door open and the false bottom extended. 60

Fig. 3 is a horizontal sectional view taken on line 3—3 of Fig. 1.

Fig. 4 is a vertical longitudinal sectional view taken on line 4—4 of Fig. 1 in a direction in which the arrows point. 65

Fig. 5 is a detail view of the device.

Similar characters of reference are employed in all of the above described views, to indicate corresponding parts.

Referring now, more particularly, to the 70 accompanying drawings there is provided a stove generally designated 1, the oven 2 of which is of a rectangular configuration and has its open front end of the body thereof removably closed by a door 3 hinged as at 4 75 to the forward edge of the bottom of the body of the oven.

Disposed on the upper surface of the bottom of the oven is a false bottom 5 which is formed on its opposite side edges with opposed ears 6, while pivotally connected to these ears are the inner ends of spaced rods 7, the outer ends of which are formed with T-heads 8 which are designed for reception with the spaced vertically arranged flanged 80 guides generally designated 9. Carried on the inner surface of the door 3, each of these flanged guides in the present instance consists of a plate like attaching body 10 having opposed flanges 11 at the sides thereof and also flanges or stops 12 which prevent accidental displacement of the heads 8 from the flanged guides. 85

With a view toward providing the improved means for either assuring of the 95 maintenance of the rods 7 substantially rigid with the flanged guides so that the false bottom will move outwardly upon the opening of the door or permitting of the sliding movement of the heads 8 in the 100 guides and allowing the door to be opened without removing the false bottom, there is provided a handle 13, the shank 14 of which is turnably mounted in the door 3, while connected to the inner end of the shank 14 is 105 a cross arm 15. Pivotedly connected to the opposite ends of the cross arm are latch bars 16, the outer portions of which are slid able

through opposed openings 17 in the flanges 11 of the guides 9. By the construction described and illustrated it is appreciated that when the handle is turned in one direction 5 the rods 16 will be moved so as to lie in the path of movement of the heads 8 and lock the heads near the upper ends of the flanged guides 9 so as to assure of the false bottom 5 being drawn outwardly from the oven and 10 over the inner surface of the door 3 upon the opening of the door to consequently draw the pan adapted to be disposed on the false bottom out of the oven thus obviating the possibility of burning the hands of the cook, 15 et cetera. When the handle is turned in the opposite direction the bars 16 will permit a passage of the heads through the flanged guides until they abut the flanges 12 permitting of the opening of the door 3 with- 20 out moving the false bottom.

It is thought in view of the foregoing description that a further detailed description of the operation of the invention is entirely

unnecessary. Likewise it is believed that the advantages of the invention will be readily apparent.

What is claimed is:-

In a device of the character described, a body, a swingably mounted door connected to the bottom thereof, a false bottom disposed within the body, flanged guides connected to the inner surface of the door, rods swingingly connected to the opposite sides of the false bottom, heads on the outer ends of the rods and slideable in the guides, a handle having its shank turnably mounted in the door, a cross arm on the inner end of the shank of the handle, latch bars pivoted to the opposite ends of the cross bar and operably mounted in the flanged guides so that when the handle is turned the bars will be moved to lock the heads in the guides or to permit of sliding movement of the heads in the guides.

In testimony whereof I affix my signature.

GEORGE J. MARION.
